UNITED STATES PATENT OFFICE.

BERTRAM E. MORELAND, OF CHICAGO, ILLINOIS.

DESIGN FOR A SAVINGS BOOK.

Application filed July 26, 1926. Serial No. 18,483. Term of patent 7 years.

To all whom it may concern:

Be it known that I, BERTRAM E. MORELAND, a citizen of the United States, residing at Chicago, in the county of Cook and State of Illinois, have invented a new, original, and ornamental Design for Savings Book, of which the following is a specification, reference being had to the accompanying drawing, forming a part thereof.

The figure is a face view of the savings book, showing my new design.

I claim:

The ornamental design for a savings book, substantially as shown.

BERTRAM E. MORELAND.
